Primary Examiner — Carla J Wright(74) *Attorney, Agent, or Firm* — Heedong Chae; Lucem, PC**CLAIM**

The ornamental design for a case for electronic communications device, as shown and described.

DESCRIPTION

FIG. 1 is a rear perspective view of a case for electronic communications device showing my new design;

FIG. 2 is a rear elevational view thereof;

FIG. 3 is a left side elevational view thereof; and,

FIG. 4 is an enlarged detail view of the encircled region of FIG. 1.

The dot-dash broken line circle in FIGS. 1 and 4 delineates a portion of the case for electronic communications device, including claimed subject matter, that is shown on an enlarged scale in FIG. 4. The dot-dash broken line that delineates the pattern in FIGS. 1, 2, and 4 represents the bounds of the claimed design.

The dashed broken lines throughout the drawing figures depict portions of the case that form no part of the claimed design.
